UNITED STATES PATENT OFFICE.

CYRUS A. GEERS, OF EDWARDSVILLE, ILLINOIS.

DESIGN FOR A ROAD-SIGN.

45,001.

Specification for Design.

Patented Dec. 9, 1913.

Application filed September 10, 1913. Serial No. 789,181. Term of patent 14 years.

To all whom it may concern:

Be it known that I, CYRUS A. GEERS, a citizen of the United States, residing at Edwardsville, in the county of Madison and State of Illinois, have invented a new, original, and ornamental Design for Road-Signs, of which the following is a specification, reference being had to the accompanying drawing, forming part thereof.

The figure is a perspective view of a road sign, showing my new design.

I claim:

The ornamental design for a road sign, as shown.

CYRUS A. GEERS.

Witnesses:

GEORGE W. CROSSMAN,
W. M. CROSSMAN.
